V. R. MELLENBRUCH

TRAFFIC SIGNAL

Filed April 15, 1922

Patented Nov. 25, 1924.

1,516,570

UNITED STATES PATENT OFFICE.

VICTOR R. MELLENBRUCH, OF BURDICK, KANSAS.

TRAFFIC SIGNAL.

Application filed April 15, 1922. Serial No. 552,863.

To all whom it may concern:

Be it known that I, VICTOR R. MELLENBRUCH, a citizen of the United States, residing at Burdick, in the county of Morris, State 5 of Kansas, have invented a new and useful Traffic Signal; and I do hereby declare the following to be a full, clear, and exact description of the invention, such as will enable others skilled in the art to which it 10 appertains to make and use the same.

The invention relates to traffic signals particularly adapted for use at intersecting streets and so constructed that when a vehicle approaches the intersection of one of 15 said streets, signalling elements will be actuated on the other street for signalling vehicles before they reach the intersection. The device is particularly adapted for use in streets where one street is designated as a 20 right of way street under all conditions.

A further object is to provide a traffic signal comprising a vehicle depressing plate disposed in the street, a semaphore arm disposed on the adjacent intersecting street and 25 actuated through a solenoid energized by an electric current in circuit with a circuit maker and breaker. Also to provide means whereby the signalling devices will be held in operated positions by delaying releasing 30 action of the circuit maker and breaker.

A further object is to provide a delayed circuit maker and breaker, said circuit maker and breaker comprising a segmentally shaped member formed from insulated material, spaced contact bars carried by said insulating member and having segmentally shaped runways for a contact ball and a pivoted arm for forcing said ball upwardly onto the inclined contact bars. Also to 35 provide means whereby the inclination of the segmentally shaped member may be varied thereby allowing the time of delayed action of the circuit maker and breaker to be varied.

With the above and other objects in view the invention resides in the combination and arrangement of parts as hereinafter set forth, shown in the drawings, described and claimed, it being understood that changes in 40 the precise embodiment of the invention may be made within the scope of what is claimed without departing from the spirit of the invention.

In the drawings:—

Figure 1 is a longitudinal sectional view 45 through the vehicle depressed member.

Figure 2 is a top plan view of the member depressed by the vehicle.

Figure 3 is a view partly in section and partly in elevation of one of the signalling 50 members.

Figure 4 is a transverse sectional view through the circuit maker and breaker casing showing a side view of the circuit maker and breaker.

Figure 5 is a top plan view of the circuit maker and breaker showing the casing in section.

Figure 6 is a perspective view of a portion 70 of the ball runway of the circuit maker and breaker.

Referring to the drawing, the numeral 4 designates a depressed member, which may be placed adjacent a street intersection where vehicles traveling thereover will pass 75 over the same and force the same downwardly. Connected to the inner end of the vehicle depressed member 4 pivotally at 7 is a connecting rod 8, which connecting rod extends into a circuit maker casing 9 and is provided with a universal connection 10 to a pivoted arm 11. The arm 11 is pivotally mounted on a vertical shaft 12 and is provided with a cam 13 cooperating with a cam 14 carried by the shaft 12 in such a manner that when the pivoted arm is moved 80 in the direction of the arrow α by a vehicle passing over the depressed member 4 the arm 15 of the pivoted arm 11 will force a contact ball 16, which is mounted on insulating member 17 upwardly on the inclined grooved contact members 18 supported in the arcuate member 19 formed from insulated material, thereby closing the circuit 85 20, energizing the solenoid 21, which pulls upwardly on the arm 22 of a pivoted member 23 disposed in the signalling box 24 adjacent the side of a street and spaced from an intersection. When the member 23 is rocked as above set forth, the arm 25 of 90

said member moves downwardly, imparting a pull on the chain 26, the upper end of which is connected to the arm 27 of the pivoted signalling arm 28, thereby moving said signalling arm 28 to the position shown in Figure 4 for signalling approaching vehicles that a vehicle is approaching an intersection. The signalling arm 28 moves downwardly upon breaking of the circuit 95 when the ball 16 rolls off the contact members 18. The contact members 18 are preferably arcuate shaped and the insulating 100 110

member 19 is hingedly supported at 29 at one of its ends and vertically adjustable at its other end by means of the adjusting screw 30, thereby allowing the inclination 5 of the contact members 18 to be changed for varying the duration of time of energizing the solenoid 21 for the reason that upon a slight inclination the ball 16 will roll back to normal inoperative position 10 shown in Figure 6 slowly, thereby allowing the signalling arm to be in operative position as shown in Figure 3 sufficiently long to allow the same to be observed. The signalling arm 28 is counterweighted by means 15 of a weight 31, which is of sufficient weight to allow the solenoid 21 to easily rock the pivoted member 23.

The vehicle depressed member 4 is returned to upper or inoperative position 20 after the vehicle wheels pass from the same by means of a coiled spring 32, one end of which is connected at 33 to one of the pivoted members 5 and the other end at 34 to the bottom of the casing 6.

25 From the above it will be seen that a street vehicle signalling device is provided which is simple in construction, positive in its operation, the parts reduced to a minimum and so constructed that the duration 30 of a signalling period may be varied as desired.

The invention having been set forth what is claimed as new and useful is:—

1. A vehicle actuated circuit maker and breaker, said circuit maker and breaker comprising a depressible and longitudinally movable member, a horizontally pivoted

arm, a connection between the depressible member and the arm, a segmentally shaped inclined member formed from insulating material and having a groove therein, said groove having imbedded therein spaced segmentally shaped conductor plates, said pivoted arm having one of its ends extending over the segmentally shaped member and a spherical member formed from conductor material disposed on the segmentally shaped member and in the groove thereof in the path of the horizontally pivoted arm. 40 45

2. A circuit maker and breaker, said circuit maker and breaker comprising a horizontally pivoted arm, means whereby upon rotation of the horizontally pivoted arm, said arm will move upwardly, one end of said arm having actuating means connected thereto, an inclined segmentally shaped member over which one end of the pivoted arm overlies, grooves contact plates segmentally shaped and carried by the segmentally shaped member, a conductor ball 60 mounted on the segmentally shaped member adjacent one end of the contact plates and in engagement with the arm and adapted to be projected up the inclined segmentally shaped member upon the rotation of the 65 arm.

In testimony whereof I have signed my name to this specification in the presence of two subscribing witnesses.

VICTOR R. MELLENBRUCH.
